(57) **CLAIM**

The ornamental design for an eyebrow trimmer, as shown and described.

DESCRIPTION

FIG. 1 is a front perspective view of an eyebrow trimmer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 2;

FIG. 11 is a perspective view showing the eyebrow trimmer in a use state 1; and,

FIG. 12 is a perspective view showing the eyebrow trimmer in a use state 2.

The broken lines in the drawings illustrate the portions of the eyebrow trimmer, which form no part of the claimed design. The dash-dot-dash broken lines encircling the enlarged views are for annotative purposes only and form no part of the claim thereof.
